UNITED STATES PATENT OFFICE.

RAYMOND CLIFFORD WHEELER, OF NORWICH, ENGLAND.

SASH-FASTENER.

1,356,677.

Specification of Letters Patent. Patented Oct. 26, 1920.

Application filed July 1, 1918. Serial No. 242,841.

To all whom it may concern:

Be it known that I, RAYMOND CLIFFORD WHEELER, subject of the King of Great Britain and Ireland, residing at "Clifton 5 House," Park Lane, Norwich, in the county of Norfolk, England, have invented certain new and useful Improvements in Sash-Fasteners, of which the following is a specification.

10 My invention relates to an improved sash fastener which has for one of its objects the enabling of the sashes to be firmly secured together when required not only when the two sashes are fully closed but when 15 one or either may be partially closed, so enabling the sashes to be opened for ventilation while remaining practically burglar-proof, and a further feature in my invention is to secure the sashes together to prevent them from rattling.

In carrying out my invention in one form I fix upon the top of the meeting rail of the upper sash and at one side of the same a metal plate, and arising out from it in 25 a vertical position is an extension provided at right angles or thereabout with a series of projecting fingers or teeth, preferably separated from each other by a given space, and these fingers or teeth may be V 30 shaped at their rear and free ends, viz., those parts nearest to the glass of the upper sash, and this part of my improved device is fixed so that a sufficient space is left (when the fastener is closed) between the 35 back of the teeth and the glass of the upper sash, to allow the hooked end of a quadrant arm, hereafter to be referred to, to comfortably pass between the glass and the said fingers or teeth.

40 Upon the top of the meeting rail of the lower sash and conveniently opposite to the fixture before referred to, I secure a metal plate provided with a pivot, upon which is mounted an arm capable of making a quadrant movement, one end of the arm being arranged to engage with the projecting fingers on the vertical piece on the upper sash when required at the same time passing between the projecting fingers. This 45 quadrant arm is slotted near the middle to allow it to be drawn backward through the agency of a tapped nut provided on the outer end of the quadrant arm which is screw threaded to receive the same. This 50 screw threaded end of the revolving arm passes between a quadrant channel acting as

a guide, which said quadrant channel is further provided with an automatic drop catch to hold the screw threaded arm in position when the fastener is in operation. 60

In the accompanying drawings:

Figure 1 is an elevation of part of a sash window showing the metal plate with fingers or teeth fixed upon the upper sash.

Fig. 2 is a sectional plan through the upper sashes looking down upon the meeting rails of the two sashes and showing one form of my complete fastener in its closed and fastening position.

Fig. 3 is a similar sectional plan showing 70 a modified form of my improved fastener when a horn projects upon the meeting rail of the lower sash occupying space adjoining the frame when a portion of the quadrant arm takes a curved form.

Fig. 4 shows an elevation of a portion of a sash window with the upper sash drawn down and my improved sash fastener shown in the locked position also in elevation.

Figs. 5, 6, and 7, show to a larger scale 80 the quadrant guide and automatic catch, Figs. 5 and 7 showing the parts in front elevation with the screw threaded end of the quadrant arm in section and Fig. 6 showing the device in plan.

Figs. 8 and 9 show respectively the engaging end of the quadrant arm in elevation and the same engaged to the fingered or toothed rack.

Like letters of reference are employed 90 as far as possible throughout to indicate like parts.

In order to enable me to better explain the construction of the sash fastener, I will 95 here preliminarily refer to the construction of the window to which my fastener is fitted, wherein *a* is the lower sash and *a'* the meeting rail of the lower sash. The upper sash is marked *b* and the meeting rail of the upper sash *b'*. The glass is marked *c* 100 and the sash frame *d* with the parting bead *d'*.

In further explanation of my invention as illustrated by Figs. 1 to 9 inclusive, I secure upon the meeting rail of the upper sash *b'*, a plate *e* having a vertical continuation *f* provided with fingers or teeth *f'* distanced apart by the spaces *f''*. The spaces *f''* are to receive and take the end of a quadrant arm hereafter referred to and the 110 fingers or teeth are arranged to engage with a projection upon the quadrant arm when

in a fastening position. This plate and its vertical extension are securely fastened to the upper sash, in any convenient manner, as by screws.

5 In explaining the simplest form of my invention I will refer to Fig. 2, where my fastener is shown in its securing position in which g is a plate secured to the meeting rail of the lower sash a^1 and is provided with a pivot g^1 upon which is mounted a quadrant arm h having a slot h^2 allowing the quadrant arm to turn upon the pivot and also permitting it to move longitudinally as required. The rear end of this arm 10 is arranged to pass through the spaces f^2 of the toothed rack and a projection at the end of the arm, h^3 , engages with the splayed back end f^3 at the rear of the tooth f^1 when required. A quadrant guide k is provided (more fully shown in Figs. 5, 15 6, and 7 to a larger scale) in which the front end of the quadrant arm h revolves. The safety catch m is pivoted at m^1 (Fig. 5) and operates automatically to hold the 20 quadrant arm in its fastened position but may be raised to release the arm.

The forward end of the quadrant arm is 25 screw threaded and is provided with a nut with an extension n^1 of the shape shown in Figs. 5 and 6, and this nut is tapped and fitted over the screw threaded termination 30 of the quadrant arm and when tightened up against a portion of the base plate g and still revolved, operates to draw the quadrant arm forward upon the pivot g^1 and so makes a tight engagement of the other end 35 of the arm with the toothed rack when required. When, however, it is desired to release the arm from the rack the nut n is 40 revolved and taken backward along to near the threaded portion of the arm when the quadrant arm can be pushed forward, released from the rack, and swung around upon the pivot releasing the entire fastener. 45 In order to better secure the quadrant arm from being opened from without, a guide or cover piece p is fixed as shown under which the rear end of the arm passes when 50 in its fastening position. The dotted lines show the fastener moved one quarter revolution and in its released position.

In Fig. 3 my improved fastener is substantially as before described but in this case the quadrant arm is of special shape 55 in order to avoid when required a projecting portion commonly called a horn above the top of the ends of the rail a^1 and I have here marked the space occupied by the horn with the letter t . In this case the fastening 60 end of the quadrant arm h is curved around as shown for the purpose of making an engagement and allowing for the position of the horn.

With further reference to Figs. 5, 6, 7, 8 65 and 9 which are drawn to a larger scale,

the parts are marked as far as possible with like letters of reference to those upon the smaller scale drawings, and the raised portion upon the plate g against which the lower part of the nut n bears when required is marked g^2 . The upper portion of this nut will also bear against the catch m and through it the guide k as well.

70 It will be readily understood that by using my improved fastener in the manner described the two sashes can be kept apart for the purposes of ventilation while being perfectly secured together to prevent them being opened in any way beyond that distance for which they have been arranged.

75 What I claim as my invention and desire to obtain by Letters Patent is:—

1. A sash fastening device comprising in combination a plate attached to the upper sash of a window, a series of fingers projecting laterally on said plate, a slotted quadrant attached to the upper cross bar of the lower sash, a vertical pivot pin on said quadrant, an arm having an elongated slot 80 engaging said pivot pin and adapted to slide longitudinally in said quadrant, and rotate through a horizontal plane about said pin, an inclined hook on the end of said arm adapted to engage with any one of said series of teeth or fingers, means for 85 drawing the sashes together and securing said arm against longitudinal movement in said quadrant, and means for securing the arm against rotation about said pivot pin 90 when the latter is in its operative position 95 with relation to said teeth or fingers.

2. A sash fastening device comprising, in combination, a lower sash, an upper sash, a plate secured to the lower cross bar of the upper sash, a vertically disposed extension 100 on said plate, a series of fingers or teeth on said vertical extension at one side thereof a slotted quadrant attached to the upper cross-bar of the lower sash, a slotted arm mounted in said slotted quadrant and having a pin and slot connection with a plate 105 on the lower sash for rotative and endwise movement, a hook on the inner end of the slotted arm adapted to engage with any one of said series of fingers or teeth, a threaded 110 portion on the outer end of said slotted arm, a nut mounted on said threaded portion and engaging the slotted quadrant to move the hook into engagement with any 115 one of said series of fingers or teeth.

3. A sash fastening device comprising, in combination, a lower sash, an upper sash, a plate secured to the lower cross bar of the upper sash, a vertically disposed extension 120 on said plate, a series of fingers or teeth on said vertical extension at one side thereof, a slotted quadrant attached to the upper cross bar of the lower sash, a slotted arm mounted in said slotted quadrant and having a pin and slot connection with a plate 125

on the lower sash for rotative and endwise movement, a hook on the inner end of the slotted arm adapted to engage with any one of said series of fingers or teeth, a 5 threaded portion on the outer end of said slotted arm, a nut mounted on said threaded portion and engaging the slotted quadrant to move the hook into engagement with any one of said series of fingers or teeth, and 10 an automatic catch pivotally mounted on said slotted quadrant to hold the slotted arm in its locked position.

4. A sash fastening device comprising, in combination, a lower sash, an upper sash, a 15 plate secured to the lower cross bar of the upper sash, a vertically disposed extension on said plate, a series of fingers or teeth on said vertical extension at one side thereof

a slotted quadrant attached to the upper cross-bar of the lower sash, a curved slotted 20 arm mounted in said slotted quadrant and having a pin and slot connection with a plate on the lower sash, for rotative and endwise movement, a hook on the inner end of the slotted arm adapted to engage with any one of said series of fingers or teeth, a 25 threaded portion on the outer end of said quadrant arm, a nut mounted on said threaded portion and engaging the slotted quadrant to move the hook into engagement 30 with any one of said series of fingers or teeth, and an automatic catch pivotally mounted on said slotted quadrant to hold the slotted arm in its locked position.

RAYMOND CLIFFORD WHEELER.
